UNITED STATES PATENT OFFICE.

WILLIAM GATEWOOD, OF NEWPORT NEWS, VIRGINIA, ASSIGNOR TO NEWPORT NEWS SHIPBUILDING & DRY DOCK COMPANY, OF NEWPORT NEWS, VIRGINIA, A CORPORATION OF VIRGINIA.

METHOD OF ERECTING VESSELS WITH LONGITUDINAL FRAMING.

1,357,699.

Specification of Letters Patent.

Patented Nov. 2, 1920.

Application filed June 17, 1919. Serial No. 304,820.

To all whom it may concern:

Be it known that I, WILLIAM GATEWOOD, a citizen of the United States, residing at Newport News, in the county of Warwick, 5 State of Virginia, have invented a new and useful Method of Erecting Vessels with Longitudinal Framing, of which the following is a specification.

In a contemporaneously pending application filed by me on May 7th, 1917, Serial No. 166,991, I have shown, described and broadly claimed a novel construction of hull for floating vessels of all types wherein I combine lightness of construction with great 10 strength and resistance to all tendencies to bendings or bucklings to which vessels or any parts thereof are ordinarily subjected.

It is well-known that vessels have been built with longitudinal frames spaced sufficiently close to locally support and stiffen the shell and inner bottom, and with longitudinal beams to locally support the decks; and with transverse frames spaced more widely to support the longitudinal frames 15 and beams, and that a similar construction has been used for stiffening the longitudinal and transverse bulkheads, the closely spaced members being commonly called "stiffeners" and the more widely spaced members 20 being commonly called "webs." In most cases where this construction has been used, the longitudinal frames are continuous through the transverse frames, which are fitted over or around the longitudinal frames, 25 but are cut for convenience at the bulkheads and the ends bracketed.

One type of this construction is illustrated in Figure 1.

The reduction in bending moment caused 40 by the use of brackets, may be utilized to reduce the number of transverses without making the longitudinals unduly large by bracketing the longitudinals to the transverses as well as to the bulkheads. This 45 construction is illustrated in Fig. 2.

To the above ends, my invention consists 50 of a novel method of erecting the framing of vessels built with longitudinal frames, wherein I first bring one of the transverse bulkheads or transverses into proper position and suitably shore it and then regulate the other transverse bulkheads and transverses in fore and aft position by means of certain of the longitudinal frames, making

suitable checks and fitting additional shoring at intervals, after which the remaining longitudinal frames are brought into position and all temporarily secured until the adjoining strakes of shell plating are in place. The longitudinals are then secured to 55 the shell plating in general before the rivets securing the longitudinals to the transverses and bulkheads are driven, or before the longitudinals are otherwise permanently secured if welding is used instead of riveting. 60

By my novel method of erection, I am enabled to avoid the extreme care in setting the longitudinal frames, which is necessary when the longitudinals are secured to the transverse members before being secured to 70 the shell plating, and, moreover, the placing of the shell plating can proceed without waiting for the longitudinal frames to be secured.

For the purpose of illustrating my invention, I have shown in the accompanying drawings, certain forms wherein the novel steps of my method can be carried out, since the same will be found in practice to give satisfactory and reliable results, although 75 it is to be understood that the various instrumentalities or steps of which my invention consists can be carried out in different ways and that my invention is not limited to the precise steps or sequence of steps as 80 herein shown and described.

Fig. 1 represents a section taken through a compartment of a vessel, showing two transverses between transverse bulkheads and two webs between shell and centerline 90 bulkhead.

Fig. 2 represents a section taken through a compartment of a vessel, showing only one transverse between transverse bulkheads, with the longitudinals bracketed to the transverse as well as to the bulkheads. 95

Fig. 3 represents a partial side elevation of a vessel, having longitudinal framing and two transverses between the transverse bulkheads.

Fig. 4 represents a partial side elevation of a vessel, having longitudinal framing and a single transverse between transverse bulkheads.

Fig. 5 represents a perspective of a compartment on a vessel, showing two transverses between transverse bulkheads. 105

Fig. 6 represents a partial section taken

through the junction of a longitudinal and a bulkhead, the left side showing the framing temporarily secured and the shell plating not yet drawn into place, while the right side 5 shows the shell plating riveted to the longitudinal and bulkhead, and the holes in the connection of the longitudinal to the bulkhead ready for reaming, if necessary, before riveting.

10 Similar numerals of reference indicate corresponding parts.

Referring to the drawings:—

Referring first to Fig. 1,—1 designates the transverse frames or transverses, and 2 the web on the center line bulkhead. 3 designates the web on the transverse bulkhead, and 4 designates the longitudinal supported by the transverse and bracketed to the transverse bulkhead.

20 5 designates stiffeners on the centerline bulkhead supported by the webs and bracketed to the transverse bulkheads.

6 designates stiffeners on the transverse bulkheads supported by the webs and bracketed at one end to the shell and at the other end to the centerline bulkhead.

7 designates the brackets located at the end of the longitudinal or stiffener, it being noticed that the spacing between transverses 30 or webs is appreciably less than the spacing between a transverse and bulkhead or between a web and bulkhead or shell. 17 designates the shell plating.

In the construction shown in Fig. 3, which 35 is a partial elevation of a vessel having longitudinal framing and two transverses between transverse bulkheads, I have designated the transverses as 1, while 14 designates the bulkheads and 16 the decks.

40 In the construction seen in Fig. 4, which is a partial elevation of a vessel having longitudinal framing and a single transverse between transverse bulkheads, 1 indicates transverses, 14 the bulkheads and 16 the decks.

I am aware of the Isherwood Patent No. 1,147,732, wherein is claimed the securing or rigidly mounting of the longitudinal frames in exact position before securing the shell 50 plating, but my invention is differentiated therefrom, since in my method I preferably do not secure the longitudinal frames in exact position until after the shell plating is in place.

55 In my method of erecting the framing of vessels built with longitudinal frames I first bring one of the transverse bulkheads or transverses into proper position and suitably shore it. I then bring the remaining 60 transverse and longitudinal frames into position and temporarily secure all, until the adjoining stakes of shell plating are in place, when the transverse members and longitudinals are secured to the shell plating 65 in general before the rivets securing the lon-

gitudinals to the transverses or bulkheads are driven, it being understood by those skilled in the art that the alining rivet holes in the connection of the longitudinal to the transverse member should be reamed if necessary to secure fair holes; or before the longitudinals are otherwise permanently secured if welding is used instead of riveting. The advantages of my invention will be understood from Fig. 6, wherein 18 designates 70 a service bolt for temporarily securing the framing, 19 designates a rivet hole in clip 20 on bulkhead 14, 21 designates a corresponding rivet hole in bracket 7, and 22 represents the distance which the parts of the 80 framing may be out of alinement before they are permanently secured to each other, and which will be eliminated when the shell plating is drawn up to the framing.

It will be apparent to those skilled in the art, that by my method of erecting, the extreme care in setting the longitudinal frames is avoided, which is necessary when the longitudinals are secured to the transverse members before being secured to the shell 90 plating, and, moreover, the placing of the shell plating can proceed without waiting for the longitudinal frames to be secured. The same order of procedure can be followed in the construction of the decks, and where 95 the bottom plating is put in place before the frame is assembled on it, the customary procedure would be followed in connection therewith.

Having thus described my invention, what 100 I claim as new and desire to secure by Letters Patent, is:—

1. The method of erecting vessels with longitudinal framing, which consists in first bringing one of the transverse members in proper fore and aft position, next regulating the adjacent transverse members in fore and aft position, by means of certain of the longitudinal frames, next temporarily securing the longitudinal frames to the transverse members until the adjacent shell plating is in place, and lastly securing said shell plating to the transverse members and longitudinal frames before permanently securing said longitudinal frames to said transverse members. 110

2. The method of erecting vessels with longitudinal framing, which consists in first bringing one of the transverse members in proper fore and aft position, next regulating the adjacent transverse members in fore and aft position, by means of certain of the longitudinal frames, next temporarily securing the longitudinal frames to the transverse members until the adjacent shell plating is in place, next securing the shell plating to the transverse members and longitudinal frames before the rivets securing said frames to said members are driven, reaming the alining rivet holes after secur- 120 125 130

ing the proper faying of the longitudinal frames against the shell plating, and lastly riveting said longitudinal frames to said transverse members.

5 3. The method of erecting vessels with longitudinal framing, which consists in first bringing one of the transverse members in proper fore and aft position, next bringing the remaining transverse and longitudinal frames into position, next temporarily securing the longitudinal frames to the transverse members until the adjacent shell plating is in place, and lastly securing said shell plating to the transverse members and longitudinal frames before permanently securing said longitudinal frames to said transverse members.

10 4. The method of erecting vessels with longitudinal framing, which consists in first

bringing one of the transverse members in proper fore and aft position, next bringing the remaining transverse and longitudinal frames into position, next temporarily securing the longitudinal frames to the transverse members until the adjacent shell plating is in place, next securing the shell plating to the transverse members and longitudinal frames before the rivets securing said frames to said members are driven, reaming the alining rivet holes after securing the proper faying of the longitudinal frames against the shell plating, and lastly riveting said longitudinal frames to said transverse members.

15 WILLIAM GATEWOOD.
